Owen Taylor,

Attorney

Owen Taylor Jr.

UNITED STATES PATENT OFFICE.

OWEN TAYLOR, OF HUNTINGTON, WEST VIRGINIA, ASSIGNOR OF ONE-THIRD TO
CHARLES C. TAYLOR AND ONE-THIRD TO DANIEL BOONE, BOTH OF HUNTING-
TON, WEST VIRGINIA.

FIREPLACE.

1,411,132.

Specification of Letters Patent. Patented Mar. 28, 1922.

Application filed August 10, 1920. Serial No. 402,533.

To all whom it may concern:

Be it known that I, OWEN TAYLOR, a citizen of the United States, residing at Huntington, in the county of Cabell and State of West Virginia, have invented certain new and useful Improvements in Fireplaces, and I do hereby declare the following to be a full, clear, and exact description of the invention, such as will enable others skilled in the art to which it appertains to make and use the same.

This invention relates to fire places and it consists in the novel features hereinafter described and claimed.

An object of the invention is to provide a fire place of simple structure having means for permitting air to circulate about the walls of the heating chamber thereof whereby the air may be heated to a maximum degree and permitted to escape into the room in which the fire place is located.

With this object in view, the fire place consists of a heating chamber made up of slabs composed of fire clay there being a grate located in the said chamber. The grate may be used for burning wood or coal or other heating means may be provided for supplying heat to the heating chamber, such means as for instance an oil or gas, or gasoline burner. A casing surrounds three sides of the heating chamber and is spaced from the same. Air ducts lead in from the front of the casing and communicate with the rear portion thereof and are adapted to lead air from the room into the casing around the fire chamber and to permit the heated air to pass from the casing into the room. The casing and fire chamber are mounted upon a base which is provided with a detachable ash box and a grate is mounted upon the floor of the fire chamber and is positioned above the said ash box.

In the accompanying drawings:—

Figure 1 is a front elevation of the fire place,

Figure 2 is a sectional view of the same, on line 2—2 of Figure 1,

Figure 3 is a vertical sectional view through the complete fire place on the plane of line 3—3 of Figure 2.

Figure 4 is a cross-sectional view on line 4—4 of Figure 1.

Figure 5 is a detailed perspective view of the chamber lining parts.

The fire place includes a base member 1

mounted upon feet 2 and having an ash box or drawer 3 slidably mounted therein. The base member 1 is provided at its top side with an opening 4 over which is located a removable grate 5. A casing 6 is mounted upon the base member 1 and a smoke pipe 7 communicates with the top side of the said casing. A plate 8 is located in the upper portion of the casing 6 and is disposed at an angle with relation to a horizontal line with its upper edge joined with the top side of the casing and its lower edge engaging the rear wall of the heating chamber hereinafter described. Air passages 9 lead through the front side of the casing 6 and pass through the plate 8. Air passages 10 lead in from the front side of the casing 6 at the lower portion thereof and have their rear ends disposed at the back of the casing 6.

The heating or fire chamber comprises side walls 11 composed of fire clay, a back rest 12 composed of the same material and located at the rear edges of the side walls 11 and a back wall 13 also composed of fire clay and cut out at its edges to rest upon the inner edges of the side walls 11. When the parts are assembled, the back wall 13 is in an inclined position within the casing 6 and spaced from the rear wall thereof and the side walls 11 are spaced from the side walls of the casing and are located between the air passages 9 at the upper portion of the casing and the air passages 10 at the lower portion thereof.

The upper edge of the back wall 13 is spaced from the top wall of the casing so that smoke may pass from the heating or fire chamber over the upper edge of the back wall 13 and out through the smoke pipe 7 in a usual manner. The passages 9 are separated from the path of escape of products of combustion by branch partitions 8 on plate or partition 8 directly over walls 11.

When coal or wood is used in the grate 15 for heating the fire or heating chamber, the ashes from the said fire may fall from the grate 15 through the grate 5 and into the ash pan or box 3. The said pan or box may be removed at intervals from the base member 1 and emptied of its contents.

When the heating or fire chamber is heated, the walls 11, 12 and 13 thereof absorb the heat and the air which is circulating about the outer surfaces of the said walls and within the casing 6 becomes heated and may pass out into the room in which the fire

place is located and effectually warm or heat the same.

From the foregoing description taken in conjunction with the accompanying drawings, it will be seen that a fire place of simple and durable structure is provided and that the same may be economically used to advantage for recovering and utilizing a maximum amount of the heat which is generated by the fire burning in the said fire place.

Having described the invention, what is claimed is:—

1. A fire place of the class described having a casing provided with a fire chamber and with front inlet and outlet openings, side members for the fire chamber spaced from the side walls of the casing to provide side air passages communicating with said openings, an inclined rear wall for the fire chamber overlapping said members and spaced from the rear of the casing to provide a back air chamber communicating with said passages, a wall at the rear of the ash pit overlapping said side members and on which said inclined rear wall rests, and an

inclined partition extending over the top of the back air chamber serving to position the side members and rear walls and apertured to communicate with the top side air passages, and branch partitions extending from said partitions to the front of the casing in line with and over said side members.

2. A fire place of the class described having a casing provided with a fire chamber and front inlet and outlet openings, side members for the fire chamber spaced from the side wall of said casing to provide top and bottom side air passages communicating with said openings, rear wall means for the fire chamber spaced from the rear of the casing to provide a back air chamber communicating with said side passage, and a partition extending over the top of the back air chamber and apertured to communicate with the side air passages.

In testimony whereof I affix my signature in presence of two witnesses.

OWEN TAYLOR.
